UNITED STATES PATENT OFFICE.

DAVID A. LEE AND THOMAS E. LEE, OF CENTREVILLE, IOWA.

MINING-MACHINE.

SPECIFICATION forming part of Letters Patent No. 601,971, dated April 5, 1898.

Application filed February 16, 1897. Serial No. 623,653. (No model.)

To all whom it may concern:

Be it known that we, DAVID A. LEE and THOMAS E. LEE, citizens of the United States, residing at Centreville, in the county of Appanoose and State of Iowa, have invented a new and useful Mining-Machine, of which the following is a specification.

The invention relates to improvements in mining-machines.

10 The object of the present invention is to improve the construction of mining-machine shown and described in Letters Patent No. 563,776, granted July 14, 1896, to James E. Lee, David A. Lee, and Thomas E. Lee, and 15 to provide simple and effective means for raising and lowering the off side of the mining-machine to cause the cutter to dip or incline downward into the substance mined or cut and also to enable the cutter to travel in 20 a horizontal plane while the machine is traveling over an uneven bottom or road-bed.

A further object of the invention is to improve the construction of the supporting-frame, strengthen the same, and afford ready 25 access to the motor when desired.

The invention consists in the construction and novel combination and arrangement of parts, as hereinafter fully described, illustrated in the drawings, and pointed out in 30 the claims hereto appended.

In the accompanying drawings, Figure 1 is a perspective view of a mining-machine constructed in accordance with this invention and showing the rear thereof. Fig. 2 is a 35 similar view showing the front of the machine. Fig. 3 is a longitudinal sectional view. Fig. 4 is a transverse sectional view on line 4-4 of Fig. 3.

Like numerals of reference designate corresponding parts in the several figures of the drawings.

1 designates a mining-machine frame consisting of a central casing 2 and front and rear platforms 3 and 4, formed integrally with 45 the casing, which is provided with a removable top or cap section 5, the upper and lower sections of the casing being provided at their contiguous edges with registering lugs 6, receiving screws or bolts 7. The casing, which 50 is rectangular in cross-section, being substantially cubical, is provided at the front and back of the lower section or body portion with

bearings 8 and 9 for a longitudinal shaft 10, and it forms a housing for a motor for rotating the longitudinal shaft and operating the 55 mining-machine.

Any suitable form of motor may be employed, but an electrical one, as illustrated in Fig. 2 of the accompanying drawings, is preferably employed, and the top or cap 5 of 60 the casing may be readily removed to afford access to the motor.

The mining-machine is supported by grooved wheels 11, running on flanged rails 12, and toothed wheels 13, running on a rack-bar 14. The flanged rail 12 constitutes one side of the track, and the rack-bar 14, which is constructed as described in the above-mentioned patent, is located at the other side of the track, and the mining-machine frame is 70 provided with suitable bearings for the stub-axes 15, upon which the toothed wheels are mounted.

The longitudinal shaft 10, which is arranged substantially as shown in the said patent, is 75 connected at its rear end by beveled gear-wheels 16 and 17 with a vertical shaft 18, and the latter has its lower end connected by similar gear-wheels 19 and 20 with a transverse cutter-shaft 21. The cutter-shaft is provided 80 at its outer end with a socket which receives the inner end of a cutter 22.

The rear vertical shaft 18 is swiveled to the mining-machine frame by a bearing-bracket 23, which permits the cutter to be turned at 85 any desired angle and to be thrown from one side of the machine to the other. The bearing-bracket 23 is composed of an upper portion, mounted in a circular opening of the rear platform of the machine-frame, and a 90 lower portion 24, extending transversely of the frame and located beneath the front platform, suitable fastening devices 25 being provided for connecting the upper and lower portions of the bracket. The upper portion of the 95 bracket 23 is circular and is provided at its periphery with teeth 26, which mesh with a horizontal screw or worm 27, disposed longitudinally of the frame in suitable bearings at the rear platform and carrying a hand-wheel 100 28 at its outer end. By this construction the cutter may be readily adjusted to the desired position. The lower portion of the bearing-bracket is provided with suitable bearings for

the cutter-shaft and is secured at right angles to the frame by a bolt 29 or other suitable fastening or locking device, and the bolt is adapted to be readily removed to permit the cutter 5 to be swung around and adjusted while the machine is in motion.

The grooved wheels 11, which are located at the front and back of the frame, are each mounted in a forked or bifurcated lower portion 10 of a vertical standard 30, provided with a tubular upper portion passing through an opening of the adjacent platform, and the tubular portion, which is interiorly threaded, is engaged by an adjusting-screw 31, swiveled 15 to and depending from a support 32. The screw is provided at its upper end with a hand-lever 33, adapted to be rotated to force the tubular standard downward or draw it upward to raise and lower the adjacent side of 20 the mining-machine, and by this construction the auger or cutter may be caused to dip into the coal or other mineral mined or may be caused to run horizontally while the machine is traveling over an uneven or slanting bottom 25 or bed.

The vertically-adjustable standard 30 is provided in its outer face with a vertical groove or way to receive the key, which is mounted in a similar groove or way of the 30 frame of the machine, whereby the standard is held against accidental rotation and the wheel is maintained in perfect alinement. The support 32 is substantially inverted-U-shaped, being provided with an opening for 35 the passage of the adjusting-screw and the tubular standard, and it is secured upon the platform of the frame by means of suitable bolts or screws passing through the same and engaging threaded sockets of the sides of the 40 support.

In order to feed the machine forward automatically, the front toothed wheel is connected by gearing with the longitudinal motor-shaft, and as the motor-shaft is rotated 45 to effect the operation of cutting it also rotates the front toothed wheel and gradually advances the machine, feeding the cutter forward. The front end of the motor-shaft is provided with a worm 33^a, which meshes with 50 a gear-wheel 34 of a front vertical shaft 35, and the latter is provided at its lower end with a worm 36, meshing with a pinion 37 of the rear axle. This construction causes a slow, steady, automatic feeding of the machine, and by rotating the cutter backward 55 the machine is reversed or moved rearward.

The gear-wheel 34 is thrown into and out of operation by a clutch-lever 38 in order to permit the cutter to operate while the machine 60 is stationary. The clutch-lever 38, which is fulcrumed between its ends on a substantially U-shaped support 39, is connected at its inner end with a sliding clutch-section 40, connected with the front vertical shaft 35 65 by a feather or spline and adapted to be moved upward and downward to interlock with and

release a clutch-section 41, carried by the gear-wheel 34. The clutch-section 40 is provided with an annular groove which receives a pin or projection of the clutch-lever, and the clutch-section 41 is cast with the gear-wheel 34. When the lower clutch-section 40 is out of engagement with the upper clutch-section 41, the gear-wheel 34 is permitted to revolve loosely on the shaft 35 without rotating the same.

It will be seen that the frame of the mining-machine is strong and durable and that, while affording a housing for a motor, it enables the latter to be readily inspected when 80 desired. It will also be apparent that the machine is adapted to be raised and lowered at one side to tilt or cant it for causing the cutter to dip into the coal or other mineral mined, and also for enabling the cutter to run 85 horizontally when the machine is traveling over an uneven or inclined track or bottom.

Changes in the form, proportion, and minor details of construction may be resorted to without departing from the spirit or sacrifice- 90 any of the advantages of this invention.

What is claimed is—

1. In a mining-machine, the combination of a frame, provided at one side with bearings, a stub-axle journaled in said bearings 95 and provided with a carrying-wheel, a support mounted on the frame at the opposite side thereof, a vertically-movable standard passing through an opening of the frame and having a bifurcated lower portion and a tubular upper portion the latter being interiorly threaded, a wheel journaled in the lower portion of the standard, a vertical adjusting-screw swiveled to and depending from the support, said screw engaging the tubular portion of the standard and adapted to raise and lower the frame, and a motor-shaft connected with and actuating the stub-shaft, substantially as described.

2. In a mining-machine, the combination 110 of a frame provided at one side with bearings, a stub-axle journaled in said bearings and having a carrying-wheel, a support mounted on the frame at the opposite side thereof, a vertically-movable tubular standard 115 passing through the frame and having an interiorly-threaded tubular upper portion, a wheel carried by the standard, an adjusting-screw swiveled to the bracket or support and engaging the standard, the vertical shaft 120 35 journaled on the frame, the longitudinal motor-shaft, gearing connecting the lower end of the shaft 35 with the stub-axle, a worm arranged on the motor-shaft, the gear-wheel 34 meshing with the worm and mounted on the 125 vertical shaft 35, the clutch-section 41 connected with the gear-wheel 34, the sliding clutch-section 40 keyed to the shaft, and a clutch-lever fulcrumed on the frame and connected with the sliding clutch-section, substantially as described.

3. In a mining-machine, the combination

of a frame provided with an opening, an inverted - U - shaped support mounted on the frame over the opening, a vertically-movable standard mounted in the opening of the frame and having a tubular upper portion and a bifurcated lower portion, the upper portion being interiorly threaded, a wheel journaled in the lower portion of the standard, and a vertical adjusting-screw swiveled to and depending from the support, said screw engaging the tubular portion of the standard and

adapted to raise and lower the frame, substantially as described.

In testimony that we claim the foregoing as our own we have hereto affixed our signatures 15 in the presence of two witnesses.
